UNITED STATES PATENT OFFICE.

OTTO PETERMANN, OF GROTON, NEW YORK, ASSIGNOR TO STANDARD TYPEWRITER COMPANY, OF GROTON, NEW YORK, A CORPORATION OF NEW YORK.

BAR MECHANISM FOR TYPE-WRITING MACHINES.

1,081,143.

Specification of Letters Patent.

Patented Dec. 9, 1913.

Application filed January 17, 1911. Serial No. 603,123.

To all whom it may concern:

Be it known that I, OTTO PETERMANN, a citizen of the Republic of Switzerland, and a resident of Groton, county of Tompkins, and State of New York, have invented certain new and useful Improvements in Bar Mechanism for Type-Writing Machines, of which the following is a full, clear, and exact description.

10. This invention relates more particularly to the means for pivotally supporting the type-bars of visible front-strike typewriting machines.

The primary object of the invention is to 15 provide a hanger in which a type-bar may be pivotally held in such a way as to have a comparatively large but narrow bearing surface between the type-bar and the hanger, and at the same time provide means whereby adjustment may be secured in order to 20 take up any wear that may occur, thus overcoming many of the objections incident to devices of this kind as ordinarily constructed.

25. Another object of the invention is to provide a simple and efficient hanger for each type-bar which may be independently supported upon the machine frame, and which hanger may be readily made and assembled.

30. A further object of the invention is to provide simple means for reducing the friction including a ball bearing for the type-bar, and to provide a hanger in which each individual type-bar may have the wear 35 thereof adjusted without removing the hanger and the type-bar from the machine.

With these and other objects in view, the invention will be hereinafter more particularly described with reference to the accompanying drawings, which form a part of this specification, and will then be pointed out in the claims at the end of the description.

In the drawings, Figure 1 is a longitudinal section of one form of machine embodying my invention. Fig. 2 is a detail plan view of the hanger and a type-bar. Fig. 3 is an enlarged vertical section, taken on the line III—III of Fig. 4; and Fig. 4 40 is a side elevation looking at the hanger from the side opposite to that shown in Fig. 1, and showing the type-bar partly broken away.

The frame 10 has a transversely-extending bar 11 provided with hooked supports

12 to which are pivoted the key-levers 13. These key-levers are arranged in groups, and each key-lever is provided with a head 14 which is pivotally held to the hooked ends of the supports 12. Each key-lever 60 is normally held in a horizontal position by means of a spring 15, one end of which is attached to the key-lever and the other end to a part of a fixed bar 16. A link 17 connects the inner end of each key-lever to a 65 type-bar 18, and each type-bar has a head 19 on which are a plurality of characters which are adapted to print upon the work sheet carried by a platen 20. The platen 20 is mounted in the transversely-movable carriage 21, and said carriage may be provided with the usual mechanisms for letter and line spacing, and said carriage and platen may be folded over the keyboard or otherwise held as desired. 75

To pivotally hold the type-bars 18, I provide a hanger 22 for each type-bar. This hanger comprises two members 23 and 24, the former serving as a supporting member, and the latter to hold and retain the type-bar properly to said supporting member. The member 23 is cut away at 25 and has two angular feet 26 which are spaced apart and provided with threaded apertures. The screws 27 pass through openings in a recessed or depressed part 28 of the machine frame 10 and engage the threaded apertures of the hanger feet 26, and said openings may be circular or in the form of slots to permit vertical adjustment of the hangers if such 90 is found necessary or desirable. The hanger member 23 has an extended portion 29 projecting upward therefrom and rigidly secured to said portion is the upper end of the clamping or bearing member 24. This member has an offset part 30 and two flange parts 31 and 32. The member 24 is bar-like in form and has openings in the upper and lower portions thereof which are in alignment with threaded openings in the 100 hanger member 23. A screw 33 passes through the openings in the upper portion of the hanger members 23 and 24, and a screw 34 passes through the openings in the lower portion of said members. The flange 105 32 does not extend inward from the portion 30 to the same extent as the part 31 so that the screw 33 may serve to hold the part 29 of the member 23 and the flange 31 rigidly together, while the part 32 may be forced 110

of the member 23 and the flange 31 rigidly together, while the part 32 may be forced 110

inward toward the member 23 by the screw 34 in order to permit relative adjustment of the two members of the bracket or hanger for a purpose to be presently described. In 5 addition to the screws 33 and 34, dowel pins 34^a may be located at the upper and lower part of the members to assist in holding them together.

The type-bar 18 may have its inner end 10 substantially circular to form a boss 35 which is adapted to fit in a space 36 formed by the offset portion 30 between the member 24 and the member 23, and substantially central of said boss 35 is a tapered opening 15 37 which is largest on the side opposed to the inner surface of the hanger member 24. An opening 38 is formed in the member 24 and tapers from the inside toward the outer surface, and said opening 38 is in alignment 20 with the opening 37 to form a recess in which is a ball 39 forming a pivotal bearing for the type-bar. The member 23 has a relatively large opening 40 concentric with the openings 37 and 38 of the type-bar and the member 24. This opening 40 is somewhat smaller than the diameter of the boss 35 of the type-bar and forms a substantially annular bearing for the type-bar.

It will be evident that by having the ball 25 bearing on one side only of the type-bar and the type-bar provided with a plane bearing surface bearing directly against the hanger on the opposite side, the said type-bar may be readily removed; that by means 30 of the direct bearing the pressure of the ball at the central portion will not be liable to bulge or bend the type-bar by reason of the pressure thereon and permits a very light type-bar to be employed which is important 35 in machines wherein it is desired that the same be light for transportation or other purposes; that by having a relatively large plane bearing surface there is not so much surface to grind and therefore 40 a good bearing may be provided with little trouble; that by the construction shown, a large, narrow but substantial wearing surface is provided for the type-bar; that by making the member 24 of the hanger of 45 spring material as steel for example, and by having the flange 22 thereof normally away from the member 23, the screw 34 may be utilized to force the part 30 inward and thereby adjust the members relatively in 50 the direction of wear; that the single ball provides an effective pivot for the type-bar; and that the hanger may be readily made and assembled and may be readily placed in 55 position on the machine frame.

60 While I show a particular form of frame and key-levers, as well as supporting means for said levers, such features are not claimed herein as they form subject matter for separate pending applications filed by me.

65 Having thus described my invention, I

claim as new and desire to secure by Letters Patent:—

1. The combination of a support, a type-bar having an annular bearing surface bearing directly against the support on one side thereof, a single ball forming a bearing for the other side of said type-bar and serving as a pivot therefor, and means for adjusting the ball in the direction of wear. 70

2. The combination of a support, a type-bar 75 having a plane bearing surface bearing directly against the support on one side thereof, and a single ball held partly by the support and forming a bearing for the other side of said type-bar and serving as a pivot 80 therefor.

3. The combination of a support having a plurality of relatively adjustable members, a type-bar having a plane bearing surface bearing directly against one of the members 85 of the support on one side thereof, a body engaging the type-bar on one side thereof opposite the bearing surface and forming a pivot for the type-bar, and means for adjusting the members and moving the pivot- 90 body in the direction of wear.

4. The combination of a support, a type-bar having a plane annular bearing surface bearing directly against the support on one side only thereof, a body engaging the type-bar 95 on one side thereof opposite the bearing surface and forming a pivot for the type-bar, and means for adjusting the body in the direction of wear.

5. In a typewriting machine, the combination 100 with a type-bar having a plane bearing portion, of a hanger comprising two members forming a space between them for the end of the type-bar, a central single ball bearing for the type-bar between one surface 105 thereof and one member of the hanger, and a relatively large and concentric plane wearing surface between the type-bar and the other member of the hanger.

6. In a typewriting machine, the combination 110 with a type-bar having a substantially circular boss, of a hanger comprising two members forming a space between them for the boss of the type-bar, and a central ball bearing for the type-bar between one surface 115 thereof and one member of the hanger, the other of said members having a relatively large central opening surrounded by a substantially annular wearing surface between the type-bar and said latter member of the 120 hanger.

7. The combination of a hanger having a tapered opening on one side and a relatively large annular bearing on the opposite side concentric with the opening, a type-bar having a central tapered opening on one side opposed to the tapered opening of the hanger, and a ball held in said openings and forming a pivot for said type-bar. 125

8. The combination of a hanger compris- 130

- ing a plurality of members providing a space and having one member provided with a tapered opening on one side thereof extending into said space, a type-bar having a 5 tapered opening on one side opposed to the tapered opening of the hanger and having one end thereof located in said space, a single ball located in said openings and forming a pivot for said type-bar, said type-bar having a plane bearing surface bearing directly against the hanger on the side opposite the ball, and means for adjusting the members of the hanger in the direction of wear.
13. 9. The combination of a hanger comprising two plate-like members providing a space and having one member provided with a tapered opening on one side thereof extending into said space, a type-bar having a 10 tapered opening on one side opposed to the tapered opening of the hanger member, and a single ball located in said openings and forming a pivot for said type-bar, said type-bar having a plane bearing surface bearing directly against the hanger on the side opposite the ball.
14. 10. The combination of a hanger comprising two plate-like members providing a space and having one member provided with a 15 opening extending into said space, a type-bar having one end located in said space and provided with an opening opposed to the opening of the hanger member, a single ball located in said openings and forming a pivot for said type-bar, said type-bar having a plane bearing surface bearing directly against the inner side of one of the hanger members on the side opposite the ball, and means for adjusting one of the members in 20 the direction of wear.
15. 11. In a typewriting machine, a hanger comprising a supporting member adapted to be secured to a part of the machine frame and adapted to hold the hanger in a vertical 25 position while in use, a plate-like member held at one end to the other member and its other end adjustable relatively thereto, said plate-like member having an opening tapering from the inside toward the outside and 30 having an offset portion forming a space between said members, a screw for securing the plate-like member at one end to the supporting member, a screw for adjusting the other end of said member, a type-bar having 35 one end located in the space between the members and having a tapered opening opposed to and in alinement with the opening of the plate-like member, and a single ball arranged in the tapered openings of the 40 type-bar and the plate member of the bracket.
16. 12. In a typewriting machine, a hanger comprising a supporting member adapted to be secured to a part of the machine frame and adapted to hold the hanger in a vertical 45 position while in use, a plate-like member held at one end to the other member and its other end adjustable relatively thereto, said plate-like member having an opening tapering from the inside toward the outside and 50 having an offset portion forming a space between said members, a screw for securing the plate-like member at one end to the supporting member, a screw for adjusting the other end of said member, a type-bar having 55 one end located in the space between the members and having a tapered opening opposed to and in alinement with the opening of the plate-like member, and a single ball arranged in the tapered openings of the 60 type-bar and the plate member of the bracket.
17. 13. The combination with a hanger having a relatively large opening surrounded by a substantially annular bearing surface, of a type-bar having a plane surface engaging the bearing surface, and a ball bearing 65 substantially central of said opening on the side of the type-bar opposite the annular bearing surface.
18. 14. The combination with a hanger having two plate-like members rigidly held together at one end and adjustably held at the other, of a type-bar having a substantially 70 circular and smooth end provided with a plane bearing surface on one side and bearing directly against one of the members, and a ball held between the type-bar on one side and the other of the members substantially central of the circular portion of the type-bar and serving as a pivot for said bar.
19. 15. The combination with a hanger having two plate-like members rigidly held together at the upper end and adjustably at the lower end, one of said members having a relatively large opening, of a type-bar having a substantially circular end having a plane surface bearing against the 75 member of the hanger having the opening, and a ball held between the type-bar on one side of one of the members substantially central of the circular portion of the type-bar and serving as a pivot for said bar.
20. 16. The combination with a hanger having a relatively large opening surrounded by a substantially annular bearing surface, of a type-bar having a plane surface engaging the bearing surface, and a ball bearing 80 substantially central of said opening on the side of the type-bar opposite the annular bearing surface.
21. 17. The combination with a type-bar having an enlarged head with a central pivot opening, of a hanger having two opposed members forming a bearing space for said type-bar head, one of said members having a tapered opening in line with the tapered opening of the type-bar, and the other mem- 85

ber having a relatively large opening concentric with the opening in the type-bar and hanger member and surrounded by an annular wearing surface between the hanger member and said type-bar, and a ball arranged in said type-bar opening and hanger member and forming a pivot for said type-bar.

18. The combination with a type-bar having an enlarged head with a central pivot opening, of a hanger having two opposed members forming a bearing space for said type-bar head, one of said members having a tapered opening in line with the 15 tapered opening of the type-bar, and the other member having a relatively large opening concentric with the opening in the type-bar hanger and hanger member and cooperating with the type-bar forming a substantially annular bearing surface, and a 20 pivot for said type-bar.

19. In a typewriting machine, a hanger comprising two members, one of which has feet adapted to be secured to a part of the 25 machine frame, and with a projecting portion, one of said members having a relatively large opening, a bar-like member vertically arranged with respect to the first-mentioned member and adapted to have one 30 end secured to said member and its other end adjustable thereon, said bar-like member having an opening tapering from the inside toward the outside and having an offset portion forming a space between said 35 members, a screw for securing the bar-like

member at one end to the supporting member, a screw for adjusting the other end of said member, a type-bar having a tapered opening opposed to and in alignment with the opening of the bar-like member and substantially central of the opening in the supporting member, and a ball arranged in the tapered openings of the type-bars and the bar-like member of the bracket. 40

20. In a typewriting machine, a hanger 45 comprising two members, one of which is adapted to be secured to a part of the machine frame, one of said members having an opening, a bar-like member vertically arranged with respect to the first-mentioned 50 member and adapted to have its upper end rigidly secured to said member and its lower end adjustable thereon, said bar-like member having an opening tapering from the inside toward the outside and having an offset portion forming a space between said members, a type-bar having a tapered opening opposed to and in alignment with the opening of the bar-like member and substantially central of the opening in the supporting member, and a ball arranged in the tapered openings of the type-bars and the bar-like member of the bracket. 55

This specification signed and witnessed this 6th day of January A. D. 1911.

OTTO PETERMANN.
